(57) **CLAIM**

The ornamental design for a fire pit and stand, as shown and described.

DESCRIPTION

This application is related to U.S. Design patent application No. 29/865,767, filed Aug. 11, 2022, entitled Fire Pit Stand, the entire disclosure of which is hereby incorporated herein by reference.

This application is also related to U.S. patent application No. 17/886,239, filed Aug. 11, 2022, entitled Portable Stove with Folding Stand, the entire disclosure of which is hereby incorporated herein by reference.

FIG. 1 is a top, front, left perspective view of a fire pit and stand showing our new design; and,

FIG. 2 is a front elevational view thereof.

The equally-dashed broken lines shown in FIGS. 1-2 are included for the purpose of illustrating portions of the fire pit and stand that form no part of the claimed design.

The surface shadings and contour lines shown in FIGS. 1-2 represent the three-dimensional character and contour of the fire pit and stand.
